(57) **CLAIM**

What is claimed is the ornamental design for a float, as shown and described.

DESCRIPTION

FIG. 1 is a perspective view of a float, showing the new design in a deployed configuration;

FIG. 2 is a front elevational view thereof;

FIG. 3 is a rear elevational view thereof;

FIG. 4 is a left-side elevational view thereof, the right-side elevational view being a mirror image thereof;

FIG. 5 is a bottom plan view thereof;

FIG. 6 is a top plan view thereof;

FIG. 7 is a front perspective view thereof, illustrated in a rolled configuration;

FIG. 8 is a left-side elevational view of FIG. 7;

FIG. 9 is a rear perspective view of FIG. 7; and,

FIG. 10 is a right-side elevational view of FIG. 7.
